BAG HANDLING MACHINERY

Wesley Dodge, Oakland, Calif., assignor to Pater-
son Parchment Paper Company, Bristol, Pa., a
corporation of New Jersey

Application April 7, 1945, Serial No. 587,157

8 Claims. (Cl. 226—49)

1

This invention relates to improvements in devices for removing a bag from a stack of bags, opening the bag and positioning the open bag to receive a charge.

In my previous Patent 2,293,937 of August 25, 1942, I have shown a bag positioning and opening device. This structure was utilized successfully in the packaging of various materials such as carrots and the like.

The present invention is concerned with improvements in the class of machines generally disclosed in my aforementioned patent, the device of the present invention being particularly characterized by the fact that it can be employed with bags of varying size and is not dependent on a supply of bags of only one length or width. It is further characterized by its rapidity of operation, the fact that it operates with great accuracy, removing each bag in succession from a stack of bags and placing it in open position to receive a charge of the material to be placed therein and, finally, by the fact that little pull or stress is placed upon a bag during movement into charge receiving position from the bag stack and opening to receive the charge.

It is in general the broad object of the present invention to provide an improved bag positioning and opening device.

A further object of the present invention is to provide an improved bag opener in which little stress is placed upon the bag.

The invention includes other objects and features of advantage, some of which, together with the foregoing, will be disclosed hereinafter, wherein the present preferred bag opening device of this invention is disclosed.

In the drawing accompanying and forming a part hereof,

Figure 1 is a side view of a form of bag opener of the present invention.

Figure 2 is an enlarged side view showing operational movement of a portion of the bag opener.

Figure 3 is a partial end view of the right end of the bag opener (Figure 2) showing the location of various parts on the shaft along the line 3—3 of Figure 1.

Figure 4 is a fragmentary view, showing the engagement of the ratchet wheel utilized in operation of the bag opener.

Figure 5 is a partial end view of the bag holder and the operating rollers.

Figure 6 is a longitudinal sectional view showing operational movements of parts at the left hand end of the bag opener as shown in Figure 1.

Figure 7 is an end view of the left hand end of the bag opener looking toward the left end of the machine along line 7—7 of Figure 1.

Figure 8 is a section along the line 8—8 in Figure 1 while Figure 9 is a section along the line 9—9 in Figure 8.

2

Figure 10 is a side elevation of a bag engaging unit in position to engage a bag from off a stack.

Figure 11 is an end view of the unit actuated to retain a bag while Figure 12 is a side elevation of the unit in this position.

10 The machine of the present invention includes a novel form of bag engaging device for attachment to a side of one bag on a stack. Means are also provided for moving the device to deliver an engaged bag to means which engage opposite sides of the bag and then open the bag while the engaging means returns to engage another bag. The several means are shown in association as in one form of machine which I have built and successfully operated. However, while they will be described in this association, it is to be understood that they can be incorporated in other and different associations as defined in the claims which appear hereinafter.

20

The frame

In the preferred form of machine shown in the drawings, a suitable supporting frame is provided as at 12 mounted upon a suitable base 13. The frame and bed are made up of suitable channel and angle irons bolted or welded together to provide the necessary support for the various machine units.

25

Weighing mechanism

30 Mounted upon the top of the frame in a receiving position is a weighing mechanism generally indicated at 14. This includes a receiving hopper 16 pivotally supported at one end of a balance arm or lever 17 pivotally mounted as at 35 18 on frame extension 32. The other end of the balance arm carries a suitable counter balance weight 19 movable along portion 21 of the balance arm.

30

The receiving hopper is made of a top portion 40 in the form of a ring 22 on which is mounted for hinged movement a plurality of cooperating conical sections 23 hinged upon the ring 22 as by rods 24 secured to extensions 26 on each conical section, the rods being passed through and rotatable in ears 27 on the ring. The several conical sections are symmetrical and cooperate to form a cone shaped hopper which opens up to permit articles deposited therein to pass on through.

50

An arm 28 is provided on the ring 22, the arm being pivotally connected by link 29 to an extension 31 on the supporting frame 32 for the balance beam 17 so that a parallel linkage mechanism is provided as a guide for the weighing hopper.

55

The hopper is filled by hand or by any suitable discharge mechanism, preferably one discharging a weighed batch. Mounted for a hinged movement on the ring 22 (Figures 1, 8 and 9) 60 is a lever arm 36 notched to engage pin 37 on

an extension 38 on one of the segments to retain the hopper segments closed. The lever 36 extends from the ring to engage a fixed stop 39 carried on an upright 41 on the frame 12 (Figures 1 and 9).

Hopper movement

The hopper is movable between a raised and a lowered position. In its raised position the hopper receives the batch prior to discharging it into a bag. In this position, lever 36 being engaged with stop 39, the several conical hopper segments are held closed. The engagement of notched arm 36 with pin 37 locks the segments together so that contents of the hopper are retained until the hopper has descended into its lower or discharge position wherein arm 36 is released from engagement with stop 39. As the hopper moves into this position, lever 36 engages stop 43, also mounted on the upright 41. In this position lever 36 is rocked and its connected segment is open. This opening movement of the segment is communicated to the other segments by suitable interconnecting levers indicated generally at 44 (see Figure 8) carried on each of the rods 24. Thus the opening movement of the segment carrying extension 38 is effective to open all the other segments and discharge the contents of the weighing hopper.

In Figures 1 and 2 I have indicated by dotted lines a suitably positioned bag 51 in place and opened to receive the hopper. The bags are delivered by a suitable bag delivery mechanism to be presently described in detail. As appears in Figures 1 and 2, the bag is retained by fingers 52-53 and 120-122. Each bag is cut away on one side adjacent the bag top so that the bag has a short side 50-A and a long side 50-B which can be engaged by fingers 120-122 while the short side is engaged by fingers 52-53. As the cone shaped weighing hopper descends into the open top of the bag to discharge its contents, the bag is spread apart and further opened. Thereupon the contents of the hopper drop into the bag forcefully, whereupon the bag drops through the frame onto a conveyor (not shown) which carries the filled bag away.

The drive

Means are provided for delivering and for opening each bag as delivered and for coordinating each bag delivery with a hopper discharge operation. This means includes a source of power such as an electric motor 71 mounted upon the frame. The electric motor has a shaft 63 on which is fastened gear 64 in mesh with gear 65 on shaft 66 mounted on suitable brackets 67 on frame 12. A pulley 68 is fastened on shaft 66 driving a belt 72 extending about pulley 73 fastened to shaft 74 mounted on frame 12 by bearings 69. Shaft 74 is maintained in axial alignment in the frame 12 by thrust collars 70. A chain 80 is passed about a sprocket 75 on shaft 74 and a sprocket 76 secured to a ratchet 78. The sprocket and ratchet rotate together freely on the shaft 77 when motor 71 is running. A driving connection is made between the ratchet 78 and the shaft 77 by pawl 79, mounted upon an arm 81 secured to the shaft by a suitable lock screw 82 engaging a flat on the shaft.

The engagement of the pawl with the ratchet is controlled by suitable means coordinating the bag delivery operation with the movement of the hopper between the discharge position and the receiving position. Rod extension 21, when in

hopper discharge position, engages a stop 83 on a slidably mounted rod 84. In the hopper receiving position the rod engages stop 86 also mounted upon the rod. Rod 84 is slidably mounted on the frame with one end thereof connected to a bell crank 87 mounted for a hinged movement on a portion of the frame. Also mounted upon the bell crank is a lever 88 biased to move in a clockwise direction by spring 89. The lever includes a notch 91 formed therein and adapted to receive a projection 92 on cooperatively adjacent lever 93. Lever 93 is also biased in a clockwise direction by spring 94 and is normally held against a pin 96 by the spring. Lever 93 projects upwardly and can engage a pin 98 carried upon the pawl 79.

With lever 88 in that position in which it appears in Figures 1 and 2, upon the hopper passing into its discharge position, the rod 84 is moved upwardly and bell crank 87 is rocked in a clockwise direction whereby notch 91 overrides and engages tooth 92 on the lever 93. When the rod is moved, upon return of the hopper to its receiving position downwardly to that position in which it appears in Figure 4, arm 93 is rocked against the tension of spring 94 and is held in this position until the rotating pawl 79, rotating with shaft 77, is moved inwardly to engage the ratchet by its pin 98 engaging the lever 93. Engagement of the pawl with the constantly rotating sprocket and ratchet results in driving of the shaft 77 whereby the bag delivery and opening is actuated.

Bag opening

The means provided for opening the bag as it advances to filling position includes a crank 101 on the shaft 77. A connecting rod 102 is extended between crank 101 and pin 106 on bar 110. Bar 110 is supported at one end for movement by a roller 111 movable in a cam track 112 provided in a plate 114 depending from the frame. The other bar end is supported by a lever 116 mounted for limited oscillating movement on the frame as at 117 and connected to the bar as at 118.

Roller 111 is mounted upon the bar 110 so that the crank 101 is effective to move the bar 110 as the roller moves in the horizontal cam track 112. On the end of the bar is mounted a bag top engaging means indicated generally at 121 and comprising a thin narrow steel finger 122 which is so moved by conjoint action of bar 110 and engaging means 121 that the finger 122 grasps the long end 50-B of a positioned bag and then retreat to pull one side of the bag open to that position in which it appears in Figures 1 and 2.

A finger 120, hinged at 119, normally engages each bag top in its closed position. As the bag is drawn into open position upon retraction of the bar 110, the bag end 50-B is retained in position by spring 124, whereupon the hopper can drop into the open bag end without displacing the bag top. As the hopper drops, the several sections are opened and the contents are released into the bag which the hopper has just entered. The drop of the contents is sufficient to pull the bag out of engagement with the fingers 52 and 53 and fingers 120 and 122, whereupon it drops through an opening in the machine frame on to a conveyor to be carried away.

Finger 120 is operated by lever 126 being moved when roller 128 comes in contact with rod 129 as bar 110 is moving forward. This

forces the roller 128 clockwise as is shown in the dotted lines in Figure 2 and separating fingers 120 and 122. Levers 126 and 127 are fastened to rod 131 which is mounted in bracket 132 mounted on bar 110. Bracket 133 is fastened to lever 127 on which is also mounted roller 134. As roller 128 comes in contact with rod 129 it raises roller 134 into a position wherein it engages and raises bar 135 to contact lever 136 which in turn, through shaft 137, rocks finger 52 clockwise thereby permitting side 50-A of a bag to enter at the same time that side 50-B enters between fingers 120 and 122. During the period of engagement of the bag by fingers 120-122 and fingers 52-53, fingers 53 and 122 are in engagement while their respective cooperating fingers 52 and 120 are moved to admit the bag. When lever 101 on shaft 77 has rotated to the point where bar 110 has advanced to its greatest extent, a release mechanism is operated which will be presently described in detail. This release causes shaft 141 to turn slightly in a counterclockwise direction of rotation. Levers 142 and 143 are fastened to one end of shaft 141. As the shaft 141 is rotated, it raises rod 129 (Figure 2) to the position as shown by dotted lines at 144, thereby releasing roller 128 and permitting finger 120 to rotate toward finger 122, to engage and grip between them the long edge 50-B of the bag. At the same time roller 134 is returned to its original level, thereby causing bar 135 to fall and engage pin 145. This in turn allows lever 136 to be pulled back by spring (not shown) to the position shown by the solid lines, thereby allowing finger 52 to rotate toward finger 53 and engage the short edge 50-A of the bag between them.

Release mechanism

The release mechanism is operated by lever 151 and arm 152 riding on cam 153 which is fastened to the end of shaft 77. A recess 154 on cam 153 is so placed on the cam that arm 152 drops into it as lever 101 is rotated and bar 110 has reached its point of maximum travel. Spring 155 (Figure 1) maintains a constant pressure of the arm 152 against the cam through shaft 141, lever 151 is fastened to frame 12 at 158 so it may swing and keep arm 152 in contact with cam 153. As arm 152 drops into recess 154 it causes lever 142 (Figure 1) to release the mechanism described above, thereby allowing fingers 52-53 and fingers 120-122 to grab a bag and hold it until the contents of the hopper have been discharged into it. This same release mechanism is used to release the bag from the pick-up unit presently described in detail.

The bag engaging unit

A supply of bags is carried in container 161 (Figures 1 and 6). A bag delivery unit, generally indicated at 162, is used to pick up each bag in turn and raise it to bag holders 52-53 and 120-122.

Bag delivery unit 162 is constructed and operated as follows: Unit 162 is raised and lowered by the cooperation of arm 163 and box cam 178 and roller 177. On cam 153, a connecting rod 164 is mounted on pin 165. As shaft 77 is rotated, cam 153 is turned in a clockwise direction and connecting rod 164 is reciprocated (Figure 1). The other end of rod 164 is connected to lever 166 by pin 167 riding in slot 168. As rod 164 travels to the left, it forces lever 166 to rotate shaft 169 counterclockwise in bearing

171 on the frame 12, thereby oscillating lever 163 which is fastened to the shaft 169. The other end of lever 163 carries a head 221 on which is pivotally mounted as at 174 a U-member 222. The bag delivery unit 162 has a threaded rod 223 which is screwed into the U-member to enable the position of the unit to be adjusted. The bag delivery unit is movable between a substantially vertical position (Figures 1 and 6) and a horizontal position (Figure 6) in which the bag hangs vertically. To turn the unit, an internal box cam 178 is mounted on frame 12 and a roller 177 is movable in this cam, the roller being mounted on one end of arm 175 while the other end of the arm is connected to U-member 222. As rod 163 is raised, the unit 162 is rotated through approximately 90° from the solid line position of Figures 1 and 6 to the broken line position of Figure 6.

The unit 162 comprises a pair of T-members 185 secured in a parallel but spaced relation on the head of threaded rod 223. A lever 181 is pivotally mounted between the T-members as at 224. The lever is biased toward the T-members by a spring 184 attached to the lever and to a pin 201 carried at one end of T-shaped trigger 183. The trigger is pivoted on one end of the T-cross bar on pin 189 at the end 191 of the bottom of the T-members. An aperture 226 is provided in lever 181 to pass the end of trigger 183. The trigger is notched as at 202 to engage the lever 181 and retain it in bag engaging position (Figure 10). A spring steel finger 186 is carried on the end of lever 181.

To open the bag and permit finger 186 to enter the bag, arms 182 are rigidly mounted on opposite ends of a rod 188 secured on leg 187 of T-shaped trigger 183; the arms extend toward the lever 181 when the latter is in latched position. The arms 182 press down on the lower side of a bag, forcing the upper edge of the short bag side upwardly. As the arms press down on the bag, they rock T-shaped trigger 183 until it releases lever 181 from retention by notch 202. When this happens, lever 181 moves in to pinch the bag side between the steel finger 186 and the corrugated end 227 of T-shaped trigger (Figures 11 and 12). The ends 228 of member 185 project below the end 227 of the T-shaped trigger to hold the bag end open.

The unit is then raised to the dotted line position of Figure 6 by reciprocation of lever 163. When the unit reaches this position, lever 143 (Figure 1) is released by cam 153 at the same time that lever 142 releases grab fingers 52-53 and 120-122; lever 143 is then rocked clockwise to engage lever 196 and rock shaft 197. This causes lever 198 to strike extension 193 on lever 181 and move the lever to latched position and to release the bag which is simultaneously caught by bag holders 52-53 and 120-122. Spring 203 on lever 204 brings levers 196 and 198 back to the position which is shown in solid lines in Figures 1 and 6.

When unit 162 pulls the uppermost bag off the stack, it tends to move the next bag forward slightly. To prevent this, a finger 250 is mounted on a shaft 251 adjacent the end of the stack. An arm 252 on the shaft is rocked upon movement of lever 143, a rod 253 extending between the two. Since lever 143 is rocked after the bag has been removed from the stack, finger 250 pushes the bags back and into alignment.

As shaft 77 continues to rotate, the recess in cam 153 will bring lever 151 back to a normal

position, ready for the next operation. Cam 178 is mounted on frame crosspiece 205. Bracket 206, and spring 207 on rod 163, assist in holding the bags in place until the bag delivery unit 162 is ready to pick up the next bag.

A spring 241, positioned between arm 242 on shaft 169 and frame 12, eases the bag engaging spring down onto the bag stack when rod 164 is released.

As shaft 77 nears the end of a full rotation, pin 98 in pawl 79 strikes lever 93 which has been returned by spring 94, thereby causing pin 98 to raise the pawl on its axis and cause the pawl to be withdrawn from ratchet 78, permitting it to rotate freely about the shaft until the operation is initiated again by movement of hopper 16. To prevent the unit from over-running when it is not being positively driven, a flat brake member 244 is secured on the frame and is urged by spring 246 against a side of cam 153.

From the foregoing I believe it will be apparent that the present machine is independent of the bag size; it is only necessary to position the bags with their uppermost edges aligned along a common plane. In this position, each bag can be successively positioned for engagement by the bag delivery unit 162 and opening in a charge receiving position.

I claim:

1. A bag engaging unit comprising a pair of spaced T-members, a lever hinged between said members, a T-shaped trigger hinged at one end of the cross bar of the trigger at the end of the stem of the T of said members, a spring between said trigger and said lever, a spring finger on an end of said lever and adapted to fit against the bottom of the stem of said T-trigger, and a pair of bag engaging presser feet secured to said T-trigger stem.

2. A bag engaging unit comprising a pair of spaced T-members, a lever hinged between said members, a T-shaped trigger hinged at one end of the cross bar of the trigger at the end of the stem of the T of said members, a spring between said trigger and said lever, the end of said T-trigger stem being adjacent to but short of the bottom end of the spaced T-members, a spring finger on an end of said lever and adapted to fit against the bottom of the stem of said T-trigger, and a pair of bag engaging presser feet secured to said T-trigger stem.

3. A bag opening and gripping unit comprising a pair of spaced members, a lever hinged at one end between said members and movable between a first bag release position and a second bag gripping position, a gripping member on the other end of said lever, a trigger member hinged between and depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion; means for moving said engaging means back and forth over a path between a bag pick-up position at said stack and a bag release position wherein the bag is suspended in a vertical open position; and means at said bag release position for substantially simultaneously gripping opposite bag sides and for relatching said lever and said trigger to release said bag from said engaging means and recondition said engaging means to engage another bag upon return of said engaging means to said stack.

the trigger end and the lever gripping member and grip said portion.

4. A bag opening and gripping unit comprising a pair of spaced members, a lever hinged at one end between said members and movable between a first bag release position and a second bag gripping position, a gripping member on the other end of said lever, a trigger member hinged between and depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion, the ends of said spaced members depending below the plane of cooperative engagement of said trigger end and said lever gripping means to force the opposite bag side away from the first bag side and provide a partially open bag.

5. In an automatic bag filling machine adapted to supply open bags individually to a filling machine associated therewith; means for positioning a stack of bags in a side-by-side relationship; means for engaging the outermost side of the outside bag in said stack comprising a pair of spaced members, a lever hinged at one end between said members and movable between a first bag release position and a second bag gripping position, a gripping member on the other end of said lever, a trigger member hinged between and depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion; means for moving said engaging means back and forth over a path between a bag pick-up position at said stack and a bag release position wherein the bag is suspended in a vertical open position; and means at said bag release position for substantially simultaneously gripping opposite bag sides and for relatching said lever and said trigger to release said bag from said engaging means and recondition said engaging means to engage another bag upon return of said engaging means to said stack.

6. In an automatic bag filling machine adapted to supply open bags individually to a filling ma-

chine associated therewith; means for positioning a stack of bags in a side by side relationship; means for engaging the outermost side of the outside bag in said stack comprising a pair of spaced members, a lever hinged at one end between said members and movable between a first bag release position and a second bag gripping position, a gripping member on the other end of said lever, a trigger member hinged between and depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion, the ends of said spaced members depending below the plane of cooperative engagement of said trigger end and said lever gripping means to force the opposite bag side away from the first bag side and provide a partially open bag; means for moving said engaging means back and forth over a path between a bag pick-up position at said stack and a bag release position wherein the bag is suspended in a vertical open position; and means at said bag release position for substantially simultaneously gripping opposite bag sides and for relatching said lever and said trigger to release said bag from said engaging means and recondition said engaging means to engage another bag upon return of said engaging means to said stack.

7. In an automatic bag filling machine adapted to supply open bags individually to a filling machine associated therewith; means for positioning a stack of bags in a side by side relationship; means for engaging the outermost side of the outside bag in said stack comprising a pair of spaced members, a lever hinged at one end between said members and movable between a first bag release position and a second bag gripping position, a gripping member on the other end of said lever, a trigger member hinged between and depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion; means for moving

said engaging means back and forth over a path between a bag pick-up position at said stack and a bag release position wherein the bag is suspended in a vertical open position; and means at 5 said bag release position for substantially simultaneously gripping (a) the side edges of the outermost bag side on each side of said lever and trigger and (b) the opposite bag side to support the bag therebetween and for relatching said lever and said trigger to release said bag from said engaging means and recondition said engaging means to engage another bag upon return of said engaging means to said stack.

8. In an automatic bag filling machine adapted 15 to supply open bags individually to a filling machine associated therewith; means for positioning a stack of bags in a side by side relationship; means for engaging the outermost side of the outside bag in said stack comprising a pair of spaced members, a lever hinged at one end between said members and movable between a first bag release position and a second bag gripping position, a gripping member on the other end of said lever, a trigger member hinged between and 20 depending from said spaced members and having a bag side engaging end thereon cooperatively positioned with respect to said other lever end to grip a first bag side therebetween when said lever is in said second position, a pair of bag edge engaging members mounted on said trigger member to engage and press against the outer edges of a bag and force upwardly the bag portion intermediate said edges, a spring biasing said lever for movement from said first to said second 25 position, and a notch in said trigger member for retaining said lever in said first position until said pair of bag edge engaging members have pressed upon said edges and forced upwardly said intermediate bag portion whereupon said lever is unlatched and is moved by said spring to engage the intermediate bag portion between the trigger end and the lever gripping member and grip said portion, the ends of said spaced members depending below the plane of cooperative engagement of 30 said trigger end and said lever gripping means to force the opposite bag side away from the first bag side and provide a partially open bag; means for moving said engaging means back and forth over a path between a bag pick-up position at said stack and a bag release position wherein the bag is suspended in a vertical open position; and means at said bag release position for substantially 35 simultaneously gripping (a) the side edges of the outermost bag side on each side of said lever and trigger and (b) the opposite bag side to support the bag therebetween and for relatching said lever and said trigger to release said bag from said engaging means and recondition said engaging means to engage another bag upon return of said engaging means to said stack.

WESLEY DODGE.
